UNITED STATES PATENT OFFICE

152,713

DESIGN FOR A FISH LURE

Jesse L. McCollum, Kaufman, Tex.

Application May 12, 1947, Serial No. 139,000

Term of patent 7 years

(Cl. D31—4)

To all whom it may concern:

Be it known that I, Jesse L. McCollum, a citizen of the United States of America, residing at Kaufman, in the county of Kaufman and State of Texas, have invented a new, original, and ornamental Design for a Fish Lure, of which the following is a specification, reference being had to the accompanying drawing, forming a part thereof wherein:

Figure 1 is a side view of a fish lure showing my new design.

Figure 2 is a top plan view.

Figure 3 is a bottom plan view.

Figure 4 is a rear view and

Figure 5 is a front view.

I claim:

The ornamental design for a fish lure, as shown.

J. L. McCOLLUM.
